UNITED STATES PATENT OFFICE.

CASSIN SNYDER, OF PHILADELPHIA, PENNSYLVANIA.

FIRE-EXTINGUISHER.

1,194,079.

Specification of Letters Patent. Patented July 21, 1914.

Application filed May 23, 1912. Serial No. 699,128.

To all whom it may concern:

Be it known that I, CASSIN SNYDER, a citizen of the United States, residing in the city of Philadelphia, county of Philadelphia, and State of Pennsylvania, have invented certain new and useful Improvements in Fire-Extinguishers, of which the following is a specification.

My invention relates to fire extinguishers, and more particularly to portable fire extinguishers which may be promptly set into operation and the fire extinguishing contents directed at will by the operator.

My invention resides in a fire extinguisher which is easily put into operation and which thereafter automatically produces fluid or gas pressure which operates either directly upon the fire extinguishing material or through the medium of a plunger or piston to expel the same, the gas or fluid pressure producing means, however, being isolated from the fire extinguisher material, that is to say, the gas or fluid pressure is produced independently of the fire extinguishing material and exerted thereon to expel the same.

My invention resides in features herein-after described and claimed.

For an illustration of some of the forms my invention may take reference is to be had to the accompanying drawing, in which:

Figure 1 is a longitudinal sectional view of a fire extinguisher involving my invention, some parts being shown in elevation. Fig. 2 is a plan view, some parts in section, on the line A—A of Fig. 1, with the dome removed. Fig. 3 is a longitudinal sectional view, some parts in elevation, of a modified form of extinguisher. Fig. 4 is a plan view, some parts in section, on the line B—B of Fig. 3, with the dome removed.

The casing or chamber forming member 1 is provided at its one end with a cap 2 screw threaded at 3 to receive stop cock 4 having the usual handle 5 for opening and closing the same. Within the casing 1, in the end next to the cap 2, is stored any suitable material, preferably liquid, such as fire extinguishing material, a well known form of which is carbon tetrachlorid. Near the other end of the chamber or casing 1 and within the same is provided a piston or plunger 6 provided with leather or other packing 7 held to the piston 6 by plate 8 held to the piston 6 by the screw 9. The piston 6 has a screw fitted shank 10 thread-ing into the shank 11, or the shank 11

and the piston 6 may be integral with each other. On the shank 11 is the guide member 12 which may conform to the cross section of the chamber 1 and fit more or less closely therein, so as to act as a guide for the piston to prevent the same from tilting and binding within the bore of the chamber 1. The member 12 is provided with a suitable opening or openings 13 to allow admission of fluid or gas under pressure back of the piston or plunger. Beyond the piston or plunger is the member 14, a metal casting or of other suitable material, fitting snugly within the casing 1 and soldered or otherwise secured thereto. The member 14 has a cavity 15 in which may be stored any suitable chemical such as bicarbonate of soda in dry or powdered form, contained, if desired, in the removable cup 15^a. At the ends of the cavity 15 are provided ledges 16 upon which rests a fragile receptacle 17, such as a glass bottle, having the ground stopper 18. This bottle 17 contains preferably an acid, such as hydrochloric or sulfuric acid, or any acid or material which when coming into contact with the chemical in the cavity 15 will freely and energetically liberate gas. The bottle 17 is here shown as of peculiar shape, as seen in plan in Fig. 2, but it is to be understood that my invention is not limited in this regard for a bottle of any suitable shape may be employed.

The member 14 has the lugs or ears 19 extending outwardly beyond the casing or chamber 1 and with these ears or lugs register corresponding ears or lugs 20 upon the dome member 21, the two members being secured together by the bolts or screws 22 which draw the two members snugly together, a gasket or packing 23 intervening to make gas tight joints which will withstand considerable pressures. The gasket 23 may be of any suitable material such as lead, rubber, or other more or less yielding material, or a corrugated copper gasket may be employed.

At its top the dome 21 has an aperture at 24 through which extends the rod 25 carrying at its lower end the member 26 resting upon or adapted to engage the bottle or other fragile vessel 17. The member 26 may be of elongated form as indicated in Fig. 2 and to prevent the same from turning about the axis of the rod 25, the rod 25 may be square in section where it passes through

the aperture 24 which may be of corresponding square shape. But any other suitable means for preventing rotation of the member 26 may be provided. Upon the outer 5 end of the rod 25 may be provided a button or head 27. Near the aperture 24 the dome has the ground seat 28 with which engages the ground member 29 secured upon the rod 25, the member 29 being here shown, by 10 way of example, as conical in shape. Within the dome 21 is the annular flange 29^a to which is secured by screw threads, brazing, or otherwise, the hollow cylinder 30 having the lower closing cap 31 through which the 15 rod 25 extends. Within the cylinder 30 and surrounding the rod 25 is provided a spring 32 which presses the member 29 against its seat 28, the other end of the spring resting upon the cap 31. Extending through the 20 bottom of the member 14 is a tube 33 which extends upwardly into the dome near the top inner wall thereof, such tube forming a passage from the dome into the space below the member 14 and above the plunger 25 or piston.

The operation is as follows: With the chamber 1 filled with fire extinguishing material, and with suitable chemicals in the cup 15^a and in the bottle 17, in case of fire, 30 the operator picks up the extinguisher and strikes the button or head 27 against a wall or other object thus forcing the rod 25 inwardly in opposition to spring 32 and causing the hammer or member 26 to break the 35 fragile receptacle 17, which allows the acid or other material to escape and come into contact with the chemical in the cup or pan 15^a with the resultant evolution of gas. The spring 32 returns the member 29 against 40 its seat 28 to prevent escape of gas, and as the gas pressure increases the member 29 is the more snugly held against its seat 28. The continued evolution of gas raises the pressure within the dome 21 and member 14 45 and the gas pressure is communicated through the tube 33 to the back of the plunger or piston. If now the handle 5 of the stop cock 4 be turned the gas pressure will propel the piston through the chamber 1 50 forcing the fire extinguishing material through the cock 4 and the operator directs the material upon the fire as the material is so expelled. In case the stop cock 4 remains shut off, or if for any other reason the gas 55 pressure attains too high a value, relief is given by the safety valve 34 held against its seat 35 by the stiff spring 36. When the pressure reaches a predetermined value the valve 34 will be lifted from its seat in 60 position to its spring 36 and relief will be given through the ports 37.

The safety valve, as indicated in Fig. 1, is so positioned that the piston or plunger may first expel all of the fire extinguishing 65 material and come to rest at the lower end

of the casing 1, and the plunger having passed the point of communication of the valve with the entry of the chamber 1, any excessive gas pressure will similarly relieve itself through the valve. It is to be understood, however, that the safety valve may be placed just below the member 14, or it may communicate with the gas producing chamber formed by the dome 21 and the member 14. 75

In Figs. 3 and 4 a modified construction is shown wherein one of the chemicals is placed in the bottom of the member 14 carrying the posts 38 having apertures receiving the pivots 39 upon a bottle or container 40 containing acid or other chemical. The receptacle 40 is closed by the cover 41 carried at the bottom of the rod 25 extending through the bottom cap 31 of the cylindrical casing member 30 in which is provided a spring 32 confined between the cap 31 and the member 29, which is ground, and adapted to engage the ground seat 28. In this case the dome 21 has a screw threaded aperture 24^a receiving the screw threads 42 upon the rod 25 90 which terminates at its outer end in the handle or knurled head 43. When it is desired to use this form of extinguisher the operator turns the handle 43 to remove the screw threads 42 from the aperture 24^a. 95 When this operation is completed the spring 32 expands lifting the rod 25, seating the member 29 in its seat 28 and lifting the cover 41 from the receptacle 40. When the cover 41 is so removed the receptacle 40 is 100 under decidedly unstable equilibrium and immediately falls, rotating upon its pivots 39 (which may be to one side of the center of receptacle 40) and emptying out the contents, as acid, from the receptacle 40 onto 105 the chemical within the member 14. Gas is now evolved as in the construction of Fig. 1 and the pressure is delivered through the tube 33 to the back of the piston or plunger, which will move forward, as soon as the 110 stop cock is opened, and expel the fire extinguishing material. A safety valve, such as shown in Fig. 1 is also applicable to the construction shown in Fig. 3 and in like positions. 115

While I have shown in both Figs. 1 and 3 a plunger or piston, it is to be understood that the plunger or piston may be omitted in those cases where the receptacle 1 is held upright or vertical, in which case the gas pressure will be exerted at the top of the fire extinguishing fluid or material and expel it preferably through a hose, communicating with the bottom of the receptacle, which may be used to direct the fluid upon the fire. 120 But where the receptacle is not to be held vertical or substantially so I prefer to use a plunger or piston as shown. 125

The tubes 33 are shown as extending well up into the dome so as to prevent entry into 126

it of the powdered or other chemical contained in the member 14.

What I claim is:

1. In a fire extinguisher, a chamber containing fire extinguishing material, a hollow member closing an end of said chamber, a dome member secured to said hollow member, a removable cup in said hollow member adapted to contain a chemical, an independent chemical container, a rod extending through said dome, a spring within said dome controlling said rod, a casing for said spring, and means controlled by said rod for bringing the chemicals into contact to produce gas pressure.

2. In a fire extinguisher, a chamber containing fire extinguishing material, a hollow member forming a closure for one end of said chamber, said hollow member having a pocket adapted to contain chemical material, ledges on said hollow member above said pocket, a fragile chemical container resting on said ledges and extending across said pocket, and means extending to the exterior of said chamber for delivering a blow to said fragile container.

3. In a fire extinguisher, a chamber having a compartment containing fire extinguishing material, an independent compartment containing chemicals for producing gas pressure, a plunger adapted to expel the fire extinguishing material and subjected to said gas pressure, and a safety valve normally separated by said plunger from the gas produced by said chemicals and adapted to be directly subjected to the gas pressure after predetermined movement of said plunger.

4. In a fire extinguisher, the combination with a casing, of a member filling one end thereof, a second member secured to said member, said members forming a chamber independent of said casing, normally isolated chemicals in said chamber, means extending to the exterior for bringing said chemicals together, fire extinguishing material in said casing, a plunger fitting within said casing and isolating said fire extinguishing material from said members, and means forming a gas passage from said chamber to the side of said plunger opposite to said fire extinguishing material.

5. In a fire extinguisher, the combination

with a casing, of a member closing one end thereof, a second member forming with said first member an independent chamber, gas producing chemicals in said chamber, a fragile container normally isolating one of said chemicals, a rod extending to the exterior of said chamber for breaking said fragile container, a spring within said chamber, and a spring casing secured to said second member, said spring normally exerting pressure on said rod away from said fragile container.

6. In a fire extinguisher, a casing containing fire extinguishing material, means forming an independent chamber closing one end of said casing, normally isolated chemicals in said chamber, means extending to the exterior for bringing said chemicals together, and means for conducting gas to said casing extending to the end of said chamber remote from said casing.

7. In a fire extinguisher, the combination with a main casing containing fire extinguishing material, of a member completely filling the bore of said casing to form an end wall thereof, a second member secured to said member, said members having cavities forming a chamber independent of said main casing, normally isolated chemicals in said chamber adapted to produce gas when brought together, said first named member having a gas passage leading from said chamber into said main casing.

8. In a fire extinguisher, the combination with a main casing, of a plug filling the bore of said casing to constitute an end wall of said casing, a member secured to said plug and forming therewith a chamber independent of said main casing, fire extinguishing material in said main casing, a plunger in said main casing isolating said fire extinguishing material from said plug, said plug having a gas passage extending from said chamber to the side of said plunger opposite to said fire extinguishing material.

In testimony whereof I have hereunto affixed my signature in the presence of the two subscribing witnesses.

CASSIN SNYDER.
